UNITED STATES PATENT OFFICE.

FRED QUIST, OF SACRAMENTO, CALIFORNIA.

RAILROAD-TIE.

1,127,277.

Specification of Letters Patent. Patented Feb. 2, 1915.

Application filed October 18, 1914. Serial No. 887,385.

To all whom it may concern:

Be it known that I, FRED QUIST, citizen of the United States, residing at Sacramento, in the county of Sacramento and State of California, have invented certain new and useful Improvements in Railroad-Ties; and I do declare the following to be a full, clear, and exact description of the invention, such as will enable others skilled in the art to which it appertains to make and use the same.

My invention relates to improvements in railway ties and particularly to specific improvements over my United States Patent Number 1,055,078. This patent covers, generally, a specific form of tie having a metal covering and a bed plate resting upon the tie and forming the top of the covering or casing. I have found that the structure of the bed plate may be improved upon by providing an inwardly projecting flange on the upper edge of one side of the casing, and by forming a groove in the adjacent edge of the bed plate, in which said flange is designed to project, this structure positively preventing the entrance of water, snow or ice, at this point.

Another object of the invention is to so position and construct a transverse tie bar as to cause the same to positively prevent longitudinal shifting of the bed plate upon the tie, and to likewise construct this bar so as to cause the same to form a rigid support for a rail brace.

With the above and minor objects in view, the invention resides in certain novel features of construction and combination herein described and claimed and shown in the drawings wherein:

Figure 1 is a top plan view of a tie constructed in accordance with my invention, a rail being applied to one end of the tie; Fig. 2 is an edge view of a tie and a vertical section through a rail thereon; Figs. 3 and 4 are vertical transverse sections as seen on the lines 3-3 and 4-4 of Fig. 1; Fig. 5 is a detail longitudinal section taken on the line 5-5 of Fig. 2; Figs. 6 and 7 are perspective views of the bed plates employed; Fig. 8 is a similar view of one of the blocks constituting a part of the tie.

In the accompanying drawings, the numeral 1 designates a wooden block having a rectangular base and a similarly shaped top, a pair of strictly upright end walls and a pair of upwardly converging side walls 2.

The block is removably positioned within a casing 3 which includes a corrugated bottom 4, a pair of upright end walls 5, an immovable side wall 6 and a removable side wall 7, the walls 6 and 7 contacting with the inclined walls 2 of the block 1. It will be noted that the upper edge of the wall 6 lies flush with the block 1, while the corresponding edge of the wall 7 is extended slightly above said top and is turned inwardly and downwardly to provide a longitudinal flange 8 which is notched at its center, as indicated at 10 in Fig. 3, said notch registering with a transverse groove 11 in the top of the block 1. Resting upon the top of the block 1, is a bed plate 12 whose opposite outer corners are provided with pairs of spaced ears 13, while its inner corners are provided with similar ears 14, said ears 13 and 14 engaging brackets 15 carried by the ends 5 of the casing, and designed to retain rail clamps 16 in active position. As clearly seen in Figs. 1, 3, 4, 6 and 7, the outer edge of the top of the plate 12, is provided with a longitudinal V-shaped groove 17 into which the flange 8 projects as most clearly seen in Fig. 4. By this simple expedient of construction, any moisture is positively prevented from entering the casing at this point.

The inner edge of the bed plate 12 is here shown as provided with a depending flange 18 which contacts with the adjacent upper edge of the wall 6, thereby preventing the entrance of water at this side of the tie. From the above, it will be seen that practically no moisture whatever is allowed to enter the casing, thereby prolonging the life of the block 1 therein.

So far, I have described but one bed plate, one casing and one block therein, but I wish to here explain that this structure is employed on each side of the track, or in other words, a bed plate 12 is located beneath each rail R, said rails being held against lateral shifting by lugs 19 which rise from said plates and engage the edges of the rail bases. In most cases, it becomes desirable to provide longitudinal draining channels 20 on the upper faces of the plates 12 and located directly beneath said bases of the rails, said channels 20 and the grooves 17 serving to conduct all water from the top of the bed plate to the ends thereof.

For the purpose of preventing spreading of the rails, a transverse sectional tie bar is

provided, said bar including a section 25 which is secured to one bed plate and a similar section 25' secured to the other. It will be noted by reference to the drawings 5 that the outer ends 26 of the sections 25 and 25' project transversely beneath the bed plates and are preferably, though not necessarily, formed integrally with said plates, the extreme terminals of the end portions 26, being extended vertically as most clearly seen at 27 in Fig. 3, and lying flush with the tops of the plates 12. To these 10 upturned ends 27, curved rail braces 28 are secured by rivets 29 or other appropriate 15 fasteners, similar fastening elements being passed through the bases of said braces and through the adjacent portions of the plates 12. When the parts are applied to use, the upper ends of the braces 28 engage the heads 20 of the rails as clearly seen in the drawings. The inner end portion of the section 25, or in other words, the portion thereof projecting inwardly from the bed plate 12 to which it is attached, is provided with a pair 25 of depending bracing flanges 30 on its opposite side edge, with a plurality of spaced teeth 31 on its lower side and with a depending pin 32. The teeth 31 are designed to interengage similar teeth 33 formed on 30 the upper side of the section 25' at its inner end, as seen in Fig. 3, in which position the pin 32 projects through an opening in said section 25' while a similar pin 34 rising from said last named section, projects upwardly through an opening in the 35 section 25, suitable cotter pins 35 being then driven through openings in the pins 32 and 34 as clearly seen in the various figures. Although this manner of connecting the opposite bed plates is desirable, it will be understood that an integral tie bar could be used to advantage, and that I do not, therefore, wish to be limited to the exact details of construction described. It is an important 40 feature, however, that the outer ends of the sections 25 and 25' act as partial fasteners for the brace 28, this becoming particularly advantageous if the plates and tie rods are formed in separate sections, since 45 the bases of said braces 28 serve to rigidly unite the plates and said outer ends, through the instrumentality of the rivets 29.

From the foregoing description taken in connection with the accompanying drawings, 50 it will be seen that a comparatively simple device has been provided which possesses a number of advantageous features.

If it is desired to obtain information disclosing the exact construction of the clamps 55 16 United States Patent 1,055,079 may be referred to, since this patent covers this feature alone.

For more specific details of the casing in which the blocks 1 are secured, United 60 States Patent 1,055,078 may be consulted,

since the construction illustrated in the present case and that illustrated in said patent is practically identical except as above pointed out.

I claim:

1. The combination with a rail supporting block and a casing surrounding the same, one side of said casing having a longitudinal downwardly and inwardly turned flange on its upper edge, of a bed plate resting upon said block and having a groove in one edge of its top, said groove receiving said flange, and means at the other edge of the plate for preventing the entrance of moisture.

2. The combination with a rail supporting block of a casing surrounding the same, one side of said casing having a longitudinal downwardly and inwardly turned flange on its upper edge, of a bed plate resting upon 80 said block and having a groove in one edge of its top, said groove receiving said flange, and a second longitudinal flange depending from the opposite edge of said bed plate and contacting with the adjacent side of 85 the casing.

3. The combination with a rail supporting block having a transverse groove in its top, of a bed plate overlying said block and having a projection on its lower side 90 fitting into said groove to prevent shifting of the plate on the block.

4. The combination with a rail supporting block having a transverse groove in its top, of a bed plate overlying said block, a transverse tie bar having one end underlying said plate and secured thereto, said end being located in the groove whereby to prevent longitudinal shifting of the plate on the block, and means for preventing lateral shifting of said plate.

5. The combination with a rail supporting block having a transverse groove in its top, of a bed plate overlying said block, a transverse tie bar having one end portion underlying said plate, the terminal of said end portion being extended vertically into contact with the outer edge of the plate and lying flush with the top thereof, and an inclined rail brace having a base 110 secured to said vertically extended terminal.

6. The combination with a rail supporting block and two pairs of angular brackets projecting from the opposite ends thereof and rising above its top, of a bed plate 120 overlying said block and having its ends contacting with the inner sides of said brackets, and spaced ears projecting over said ends and contacting with the sides of 125 said brackets, whereby longitudinal and transverse shifting of the bed plate is prevented.

7. A device for the purpose set forth comprising a rectangular bed plate having a longitudinal groove in one edge of its 130

top, a flange depending from the opposite edge of said plate, a tie rod having its outer end underlying and formed integrally with said plate, the inner end of said rod 5 projecting laterally from the flanged edge thereof and spaced ears projecting from the opposite ends of the plate.

In testimony whereof I have hereunto set my hand in presence of two subscribing witnesses.

FRED QUIST.
